(57) **CLAIM**

The ornamental design for a curtain quick release, as shown and described.

DESCRIPTION

FIG. 1 is a top front perspective view of a curtain quick release showing our new design;

FIG. 2 is a first side view thereof;

FIG. 3 is an opposite side view thereof;

FIG. 4 is a rear view thereof;

FIG. 5 is a front view thereof;

FIG. 6 is a top view thereof; and,

FIG. 7 is a bottom view thereof.

The broken lines in the figures show portions of the curtain quick release which form no part of the claimed design. Additional broken lines in FIG. 1 show environment and form no part of the claimed design.

1 Claim, 5 Drawing Sheets

US D1,012,551 S
